SAFETY RAZOR

William G. Adams, Richmond, Va.

Application March 25, 1931, Serial No. 525,274
Renewed January 14, 1933

35 Claims. (Cl. 30—12)

The invention relates to razors and more particularly to those of the so-called safety type and has for its principal object the provision of a novel razor of the popular Gillette type but characterized by the fact that the parts, while readily movable, are preferably so connected that in cleaning or drying the razor after use there is no occasion for the separation of the parts, thereby avoiding danger of dropping, losing or 10 misplacing any of them and greatly facilitating handling, particularly in the insertion or removal of the blade.

In other words, it is an important object of the invention to provide a safety razor of the replaceable blade type in which the handle is preferably inseparably connected to the body and the blade retaining cap pivoted to the latter so that the razor may be opened to permit ready insertion of the blade and to facilitate cleaning without 20 the parts ever becoming actually separated.

Another important object of the invention is to provide a razor in which the blade is clamped between the body and a movable cap, the former being carried by a swiveled handle and the latter 25 having screw means cooperating with the handle for applying a variable degree of pressure upon the blade for flexing the same.

Another object is to provide a razor as described above having movably and inseparably connected 30 body and cap members arranged to swing relatively from and toward each other for opening and closing, in which the position of the axis for swinging movement is so controlled that upon return of the members from open toward closed 35 position the elements of the screw means carried by the relatively swinging members will approach each other in a manner assuring their operative axial alignment.

Another object is to provide a razor of the Gillette type with movably but inseparably connected 40 body and cap members and in which the removable blade is carried by the cap member which is so connected with the body member as to be lifted with respect thereto when the razor is opened 45 up so that the edge of the blade will be entirely out of contact with the body when the cap swings to open position, thereby avoiding dulling of the edge.

Another object is to provide a razor such as is 50 above described, in which, regardless of whether the blade is carried by the swinging cap member or remains seated on the body during the relative rotary movement of the cap and body the cutting edge of the blade will be prevented from coming 55 into damaging contact with any of the razor parts.

A more specific object of the invention is to provide a razor having a body carried by a handle and carrying a pivoted cap and incorporating spring means between the cap and body which will operate to maintain the cap in elevated position with respect to the body when the cap portion is released from clamping engagement with the body portion. 60

Another specific object of the invention is to provide, in one modification, a razor in which a species of cam or wedge means is provided for the purpose of not only lifting the cap with respect to the body upon disconnection from the handle but also sliding it transversely of the longitudinal axis or center line of the body so that 70 a threaded stud carried by the cap and cooperating with the handle for securing the parts together in clamping relation to the blade may clear the opening provided for its reception without necessitating excessive cutting away either at the 75 end of the stud or the edge of the socket for the reception thereof.

An additional object is to provide a razor possessing the above mentioned characteristics and advantages and which will at the same time be 80 simple and inexpensive to make and assemble, easy to use, readily kept clean and sanitary, positive in action, efficient and durable in service, and a general improvement in the art.

To the attainment of the foregoing and other 85 objects and advantages, the invention preferably consists in the details of construction and the arrangement and combination of parts to be hereinafter more fully described and claimed, and illustrated in the accompanying drawings in 90 which:

Figure 1 is an elevation of one form of a razor constructed in accordance with my invention, looking at one end thereof, and showing it in 95 fully closed or operative position.

Figure 2 is a similar view showing the cap released from connection with the handle resulting from rotation of the latter.

Figure 3 is a similar view showing the cap carrying the blade swung to open position. 100

Figure 4 is a plan view of what is shown in Figure 1.

Figure 5 is a cross section taken on the line 5—5 of Figure 2.

Figure 6 is a plan view of what is shown in Figure 3.

Figure 7 is a cross sectional view through the 105 razor taken axially of the handle.

Figure 8 is a fragmentary detail perspective 110

view showing the spring means for lifting the cap.

Figure 9 is a fragmentary side elevation showing the modified form of the invention in which 5 a different type of spring means is employed for maintaining the cap in elevated position after the clamping means is released.

Figure 10 is a similar view showing the cap in 10 full lines disconnected from the handle and in dot and dash lines swung to open position,

Figure 11 is a sectional view taken axially of the handle and transversely of the body and cap,

Figure 12 is a cross section taken on the line 12-12 of Figure 9,

Figure 13 is a cross sectional view on the line 15 13-13 of Figure 15, illustrating another modification, with the cap in closed position,

Figure 14 is a similar view with the cap in 20 open position, and

Figure 15 is a fragmentary plan view with 25 parts in section, showing the form illustrated in Figures 13 and 14.

Referring more particularly to the drawings, and especially to Figures 1 to 8, inclusive, I have 30 shown my razor as comprising a body member 16 of elongated rectangular shape and of plate-like form with its side edges formed with guards defined by a series of curved prongs 17. The upper or outer face of this body is longitudinally grooved, as at 18, this groove being probably 35 actually formed by pressing out the metal, the resultant hump or ridge at the underside being indicated at 19. The purpose of the groove is to cooperate with means on the cap to be described for securing the blade properly in position, as will be explained.

Carried by the body 16 and preferably inseparable therefrom but movable relative thereto is a handle 20 of cylindrical form having one 40 end reduced to define a neck 21 terminating in a flange or head 22 located at the underside of the body and connected thereto for rotation with respect thereto by means of a plate 23 on the underside of the body having an inwardly extending flange 24 underlying the head or flange 22. This therefore constitutes a swivel connection. This swiveled end of the handle is formed with a threaded socket 25 registering with or in 45 coaxial relation to an opening 26 in the body. Where the plate 23 is attached, the ridge 19, if 50 provided, is necessarily interrupted, as shown in Figure 5.

The razor further includes a cap 27 between which and the body 16 is arranged the blade 28 55 which is intended to be one of the numerous makes of the Gillette type on the market. This cap is of elongated rectangular shape and is concavo-convex in cross section and of substantially the same dimensions as the body 16, ignoring the prongs, that is to say of the same 60 length as the body and of a width corresponding substantially to the width thereof at the base of the prongs on the opposite sides. In razors of this type which are well known to the trade 65 the cap is held in place simply by the provision of a threaded stud thereon passing through a hole in the body and engaged within a threaded socket in the handle corresponding to the socket 25 in the present instance. However, as it is an 70 important feature of my invention to maintain the cap and the body in permanently associated but relatively movable relation, I provide arms 29 located at opposite ends of the body and pivoted thereto as at 30, these arms having their 75 other ends pivoted at 31 to the ends of the cap

27. It is highly desirable that the cap when released from clamping engagement be maintained in elevated position with reference to the body portion and to effect this I provide at each end of the body a small leaf spring 32 located at a cut-away portion 33 and which has one end anchored within a slot 34 at one end of the cut-away portion and which has its other end anchored within a slot 35 and in a lug 36 on the arm 29. This spring arrangement and mounting are such that the arms 29 normally have their free ends urged away from the body, thereby lifting the cap 27 with respect to the latter. The cap is shown as having its corners provided with the usual lugs 37 engaging within the cut-away corners 38 of the blade, and as further having a longitudinally extending rib 39 engaging within the usual slot 40 in the blade, this rib being opposite the groove 18. At its center the underside of the cap carries the usual threaded stud 41 adapted to pass through the opening 26 and to be received within the threaded socket 25.

It will be observed that the cap is freely swingable with respect to the body and, viewing Figures 1, 2 and 3 in sequence, the action will be readily seen. When the razor is in use the blade 28 is clamped firmly between the body 16 and the cap and is flexed owing to the concavity of the inner face of the latter which cooperates with the convexity of the outer face of the former. The edges of the blade project beyond the body so as to be operative where exposed between the prongs 17 when the razor is used in the customary manner. When it is desired to clean the 110 razor or remove an old blade or put in a new one, it is first necessary to rotate the handle 20 in a counter-clockwise direction whereupon the stud 41 will be unscrewed from within the socket 25. The springs 32 then maintain the arms 29 and 115 consequently the cap, the latter carrying the blade with it, away from the body as shown in Figure 2. The user then engages his thumb and a finger against the projecting ends of the blade and swings it, together with the cap, upwardly 120 and outwardly with respect to the body, as shown in Figure 3, whereupon the blade may be very quickly and easily removed and replaced by a new one. If it is merely desired to cleanse the parts, it is not necessary to open up the device 125 fully as it may be simply partly opened and held under a stream of water from a faucet. The great importance in providing the springs to maintain the cap in elevated position with respect to the body is that when the cap is swung 130 into the open position and subsequently swung back, the edge of the blade will clear or be spaced from the body so as not to be abraded and dulled by contact therewith. Moreover this maintenance of the axis about which the cap is swung 135 in this elevated position, is important in that it serves, when the cap swings toward its closed position with respect to the body, to assure return of the elements of the screw means to the same position they occupied when disengaged prior to 140 swinging of the cap and therefore into reengaging relation with their axes substantially aligned.

In the form of the invention disclosed in Figures 9 to 12, inclusive, the general structure is the same as that above described except that 145 there is a different spring arrangement for maintaining the cap elevated with respect to the body after the handle is unscrewed. Referring to these figures in detail, the numeral 16^a represents the body which is identically the same as the 150

body 16 above described except that the cut-away portions 33 are not necessary. There are the same prongs 17, the groove 18, projection 19, handle 20, neck 21, head 22, retaining member 23, flange 24, and socket 25, as in the first described form. Likewise, the cap 27 with corner lugs 37, rib 39, and stud 41 are the same. Of course, identically the same blade 28 with its cut-away corners 37 and slot 40 is employed.

10 The difference lies only in the arm and spring arrangement. In this form I provide at each end of the body 16^a an arm 42 pivoted to the body 43 and pivoted at 44 to the cap. Each pivoted end 43 is formed with a heel or abutment shoulder 45 and they both engage against the ends of an elongated leaf spring 46 secured against the underside of the body 16^a.

This form operates in identically the same manner as the first described form in so far as 20 broad principles are concerned. The point is that as the heels 45 are inclined with respect to the longitudinal axes or center lines of the arms 42 there is a tendency for the springs 46 to swing these arms 42, and consequently the cap 27, carrying the blade, away from the body 16^a after the handle 20 is turned counter-clockwise to disconnect the socket 25 from the stud 41. The action brought about by the springs 46 cooperating with the arms is for the same purpose as in the 30 first described form of the invention, namely, to prevent contact of the edge of the blade 28 with the body 16^a when the cap is swung into open position and to return the screw elements, that is the stud 41 and socket 25, when the cap is swung in closed relation to the body, to the same position these elements occupied when last released so as to assure their axial alinement for reengagement.

In Figures 13 to 15, inclusive, I have illustrated 40 another form of the invention in which means is provided for shifting the cap transversely with respect to the body. In both of the first described forms it should be noted that on account of the swinging movement of the cap with respect to the body it is necessary either to make the opening 26 comparatively large or else to bevel off the end of the stud 41 so as to avoid interference with the edge of the opening. To avoid having the hole 26 excessively large or cutting away any 50 portion of the end of the stud 41, this last modification may be resorted to. Referring to this form in detail, it will be noted that I have shown a body 16^b corresponding to the bodies 16 and 16^a and similarly provided with prongs 17, groove 55 18 and ridge 19. Identically the same cap 27, with its details, is provided as in the first described forms. The difference in this form resides in the spring and arm means for maintaining the cap 27 away from the body when the handle is unscrewed. Actually, I provide at each 60 end of the body an arm 47 pivoted at one end, as shown at 48, to the cap and having its other end slotted at 49 for the passage of a screw 50, or the like, which passes into the body 16^b. The 65 spring means comprises a spring member 51, conveniently a piece of spring wire of proper gauge, having one end fitting within a recess 52 in the arm 47 and its other end formed as an eye 53 through which the screw 50 passes. The body 70 16^b is formed with a cut-away portion 54 at one end of which is an inclined ledge 55 with which cooperates a similarly inclined shoulder 56 on the arm 47. The inclined surfaces 55 and 56 lead to shoulders 57 and 58, respectively, on the 75 body and arm.

In general, the operation of this form is the same as that of the two preceding forms, that is to say, when the handle is in tightened relation to the cap the latter holds the blade flexed between itself and the body, the surfaces or shoulders 57 and 58 being then in abutting engagement. When it is desired to open the razor to change the blade, unscrewing of the handle with the resultant release of its engagement with the stud on the cap elevates the cap above the body and permits the springs 51 at the ends of the body to hold the arms 47 in the inclined position shown in Figure 14. During this operation shoulders 58 slide out of engagement with the shoulders 57 and the inclined shoulders 56 ride over the inclined surfaces 55, thereby permitting the cap 27 to shift laterally so that the stud thereon will be in substantially coaxial relation to the handle.

In all forms of the invention here illustrated it will be observed that I have provided a construction wherein the handle, body and cap are inseparable though relatively movable. Clearly, there is no difficulty to be encountered in effecting cleansing as this may be readily done when the elements are partially disconnected by reverse 100 rotation of the handle. In all forms it will be noted that ample provision has been made to maintain both the cap and the blade away from the body so that the edge of the blade will not contact with the latter and be dulled as the result when the cap is swung to open position. The device is bound to be convenient inasmuch as there is no need for handling a plurality of pieces as is necessary in the ordinary type of Gillette razor and consequently no likelihood of dropping 110 or misplacing any of them. From a sanitary standpoint there cannot possibly be any objection as all the parts of any form of the device may be readily cleaned by the action of a stream of water issuing from a faucet.

From the foregoing description and a study of the drawings it will be apparent that I have provided a safety razor closely resembling the well known and popular type referred to and which not only possesses all the advantageous 120 features thereof but which possesses the additional characteristics which will render it still more convenient to use without in any way adding to the complexity of the structure or the cost of manufacture. It is thought that the construction, operation and advantages should be readily apparent to one skilled in the art without further explanation.

While I have shown and described the preferred embodiments of the invention, it should 130 be understood that the disclosure is merely an exemplification of the principles involved as the right is reserved to make all such changes in the details of construction as will widen the field of utility and increase the adaptability of the 135 device provided such changes constitute no departure from the spirit of the invention or the scope of the claims hereunto appended.

Having thus described my invention, I claim:

1. A safety razor comprising the combination 140 of a body having an opening therethrough, a handle adapted for connection to the body and having a threaded socket coaxial with said opening, a cap having a threaded stud engageable within said socket, a blade clamped between the 145 body and the cap, and means for flexibly and permanently connecting the cap with the body, said means comprising arms pivoted at one end to the body and pivoted at their other ends to the cap.

2. A safety razor comprising the combination of a body having an opening therethrough, a handle for said body and including means having a threaded socket, a cap having a threaded stud 5 engageable within said socket for clamping a blade between the body and the cap, means for flexibly and permanently connecting the cap with the body, said means comprising arms pivoted at one end to the body and pivoted at their other ends to the cap, and resilient means urging said cap away from the body. 10
3. A safety razor comprising the combination of a body having an opening therethrough, a handle swivelly connected with the body and having a threaded socket coaxial with said opening, a cap having a threaded stud engageable within said socket, a blade clamped between the body and the cap, means for flexibly and permanently connecting the cap with the body, said means comprising arms pivoted at one end to the body and pivoted at their other ends to the cap, and resilient means urging said cap away from the body, said resilient means being connected with the body and said arms. 15
4. In a safety razor, a body provided with guards and having an opening therein, a handle arranged with its axis at right angles to the body and swivelly connected therewith and having a threaded socket coaxial with said opening, a cap, a blade interposed between the body and the cap, means on the body and the cap coacting with means on the blade for positioning the latter, a threaded stud on the cap adapted to pass through said opening and be received within said socket, arms pivoted at one end to the body and pivoted at their other ends to the cap, and spring means urging said cap away from the body, said resilient means being connected with the body and said arms. 20
5. In a safety razor, a body provided with guards and having an opening therein, a handle arranged with its axis at right angles to the body and swivelly connected therewith and having a threaded socket coaxial with said opening, a cap, a blade interposed between the body and the cap, means on the body and the cap coacting with means on the blade for positioning the latter, a threaded stud on the cap adapted to pass through said opening and be received within said socket, arms pivoted at one end to the body and pivoted at their other ends to the cap, and spring means connected with the body and engaging said arms for urging the cap away from the body when the handle is unscrewed from engagement with the stud. 25
6. In a safety razor, a body provided with guards and having an opening therein, a handle arranged with its axis at right angles to the body and swivelly connected therewith and having a threaded socket coaxial with said opening, a cap, a blade interposed between the body and the cap, means on the body and the cap coacting with means on the blade for positioning the latter, a threaded stud on the cap adapted to pass through said opening and be received within said socket, arms pivoted at one end to the body and pivoted at their other ends to the cap, and spring means connected with the body and engaging said arms for urging the cap away from the body when the handle is unscrewed from engagement with the stud, said spring means comprising leaf springs anchored at one end to the body and having their other ends anchored within slotted lugs on said arms. 30
7. In a safety razor, a body provided with guards and having an opening therein, a handle arranged with its axis at right angles to the body and swivelly connected therewith and having a threaded socket coaxial with said opening, a cap, a blade interposed between the body and the cap, means on the body and the cap coacting with means on the blade for positioning the latter, a threaded stud on the cap adapted to pass through said opening and be received within said socket, arms pivoted at one end to the body and pivoted at their other ends to the cap, and spring means connected with the body and engaging said arms for urging the cap away from the body when the handle is unscrewed from engagement with the stud, said spring means comprising a leaf spring 35
- extending longitudinally of and secured to the body, and heels on said arms inclined with respect to the longitudinal center lines thereof and engaging said spring. 40
8. In a safety razor, a body provided with guards and having an opening therein, a handle arranged with its axis at right angles to the body and swivelly connected therewith and having a threaded socket coaxial with said opening, a cap, a blade interposed between the body and the cap, means on the body and the cap coacting with means on the blade for positioning the latter, a threaded stud on the cap adapted to pass through said opening and be received within said socket, arms pivoted at one end to the body and pivoted at their other ends to the cap, and spring means connected with the body and engaging said arms for urging the cap away from the body when the handle is unscrewed from engagement with the stud, the body and arms being formed with transverse shoulders normally contacting when the cap is in clamping relation to the blade and being formed with inclined surfaces enabling the cap to slide transversely with respect to the body upon disengagement of the stud from the socket. 45
9. A safety razor comprising a body portion provided with guard means at opposite longitudinal edges thereof, said body portion having an opening therein, a handle member adapted to cooperate with said body portion, a cap having a central stud adapted to pass through the opening in said body and means for cooperating with said stud adapted to clamp a blade having a plurality of cutting edges between said cap and body, and means for resiliently connecting said cap and body comprising arm or lug members each of which is pivotally connected to said cap along a line parallel to one of the said guard members, the opposite ends of said arm or lug members being loosely connected to said body portion, 50 said resilient means being adapted upon the release of the clamping pressure to maintain the pivotal point of said cap at an appreciable distance from the body portion, said loose connection being adapted to permit clamping action between said cap and body when said clamping means is applied. 55
10. In a safety razor comprising a body and a cap adapted to have a blade interposed therebetween, means permanently and movably connecting the cap with the body and enabling the former to have swinging movement about an axis constantly parallel with the longitudinal center of the body and cap, handle operated screw means for moving the cap into clamped or released relation to the interposed blade and shifting the axis of rotation of the cap toward or away from the body in a direction substantially perpendicular to the face of the body, and resilient means for maintaining the cap in released position with its axis 60 of rotation in said shifted relation to the body. 65
11. In a safety razor, a body and a cap adapted to have a blade interposed therebetween, said body being provided with guards and having an opening therein, a handle arranged with its axis at right angles to the body and swivelly connected therewith, means on the body and the cap coacting with means on the blade for positioning the latter, screw means connecting the cap and the handle for moving the former into or out of clamping relation to the blade, arms pivoted at one end to the body and pivoted at their other ends to the cap, and spring means connected with the body and engaging said arms for urging 70
12. In a safety razor, a body and a cap adapted to have a blade interposed therebetween, said body being provided with guards and having an opening therein, a handle arranged with its axis at right angles to the body and swivelly connected therewith, means on the body and the cap coacting with means on the blade for positioning the latter, screw means connecting the cap and the handle for moving the former into or out of clamping relation to the blade, arms pivoted at one end to the body and pivoted at their other ends to the cap, and spring means connected with the body and engaging said arms for urging 75

- the cap away from the body when the screw means is released.
11. In a safety razor, a body provided with guards and having an opening therein, a handle arranged with its axis at right angles to the body and swivelly connected therewith, a cap, the cap and body being adapted to have a blade interposed between them, means on the body and the cap adapted to coact with means on the blade for positioning the latter, screw means connecting the cap and handle for moving the former into or out of clamping relation to the blade, arms pivoted at one end to the body and pivoted at their other ends to the cap, and spring means connected with the body and engaging said arms for urging the cap away from the body when said screw means is released, said spring means comprising leaf springs anchored at one end to the body and having their other ends anchored within slotted lugs on said arms.
12. In a safety razor, a body provided with guards and having an opening therein, a handle arranged with its axis at right angles to the body and swivelly connected therewith, a cap, said cap and said body being adapted to have a blade interposed between them and having means adapted to coact with means on the blade for positioning the latter, screw means on the cap and handle cooperating to move the former into or out of clamping relation with the blade, arms pivoted at one end to the body and pivoted at their other ends to the cap, spring means connected with the body and engaging said arms for urging the cap away from the body when said screw means is disengaged, said spring means comprising a leaf spring extending longitudinally of and secured to the body, and heels on said arms inclined with respect to the longitudinal center lines thereof and engaging said spring.
13. In a safety razor, a body provided with guards and having an opening therein, a handle arranged with its axis at right angles to the body and swivelly connected therewith, said cap and body being adapted to have a blade interposed between them and being provided with means adapted to coact with means on the blade for positioning the latter, screw means on the cap and handle cooperating to move the former into or out of clamping relation to the blade, arms pivoted at one end to the body and pivoted at their other ends to the cap, and spring means connected with the body and engaging said arms for urging the cap away from the body when said screw means is disengaged, the body and arms being formed with transverse shoulders normally contacting when the cap is in clamping relation to the blade and being formed with inclined surfaces enabling the cap to slide transversely with respect to the body upon disengagement of said screw means.
14. A safety razor comprising a body portion provided with guard means at opposite longitudinal edges thereof, said body portion having an opening therein, a handle member adapted to cooperate with said body portion, a cap, said cap and body being adapted to have interposed therebetween a blade having a plurality of cutting edges, coacting means on the body and cap for effecting or releasing clamping engagement with the blade, and means for resiliently connecting said cap and body comprising members each of which is pivotally connected to said cap along a line parallel to one of said guard members, the opposite ends of said members being loosely connected to said body portion, said resilient means being adapted upon release of the clamping en-
- gagement to maintain the pivotal point of said cap at an appreciable distance from the body portion, said loose connection being adapted to permit clamping engagement between said cap and body when said clamping engagement is effected.
15. A safety razor comprising a body and a cap adapted to have a blade interposed between them, means for moving the cap and body relatively to clamp or release the blade, and means for connecting the body and cap comprising arms directly and movably connected at their corresponding ends with the body and cap respectively at opposite sides of the longitudinal center thereof.
16. A safety razor comprising a body and a cap adapted to have a blade interposed therebetween, means for moving the cap and body relatively to clamp or release the blade, and movable members directly connected at one end to the body at one side of a plane passing through the longitudinal center of the body and cap and at their other ends to the cap at the other side of said plane.
17. A safety razor comprising a body and a cap adapted to have a blade interposed therebetween, means for moving the cap and body relatively to clamp or release the blade, and means for connecting the body and cap comprising spring actuated arms directly and movably connected at their corresponding ends with the body and cap respectively at opposite sides of the longitudinal center thereof.
18. A safety razor comprising a body and a cap adapted to have a blade interposed therebetween, means for moving the cap and body relatively to clamp or release the blade, movable members directly connected at one end to the body at one side of a plane passing through the longitudinal center of the body and cap and connected at their other ends to the cap at the other side of said plane, and springs connected with said movable members and reacting against the body.
19. A safety razor comprising a body and a cap adapted to clamp a blade between them, handle operated screw means connected with the cap for moving the same toward or away from the body to clamp or release the blade, respectively, and means directly connected with the body and cap for shifting the latter laterally with respect to the axis of the screw means in substantially parallel relation to the former upon release of said screw means.
20. A safety razor comprising a body and a cap adapted to clamp a blade between them, a handle, coacting screw members on the cap and handle for moving the former toward or away from the body to clamp or release the blade, respectively, and means directly connecting the body and cap for shifting the latter laterally in substantially parallel relation to the former upon disengagement of the screw members, said cap being pivotally connected with said last named means and swingable laterally upon disengagement of the screw members, said lateral shifting of the cap preventing interference of said screw members with each other upon lateral swinging of the cap.
21. In a safety razor comprising a body and a cap adapted to have a blade clamped therebetween, movable means for connecting said body and cap comprising arms the ends of each of which are connected respectively to the body and the cap on opposite sides of a median line common thereto, and screw means for moving the

body and cap relatively to clamp or release the blade, spring means connected with said first named means for moving the cap laterally with respect to the body for compensating for loss of alinement of said screw means due to the lateral shifting of the cap with respect to the body resulting from the arcuate movement of said arms during releasing of the blade clamping means.

22. A safety razor comprising a body and a cap adapted to clamp a blade between them, handle operated screw means connected with the cap for moving the same toward or away from the body to clamp or release the blade, respectively, and spring operated means directly connected with the body and cap for shifting the latter laterally with respect to the axis of the screw means in substantially parallel relation to the body upon release of said screw means.

23. A safety razor comprising a body and a cap adapted to clamp a blade between them, handle operated screw means connected with the cap for moving the same toward or away from the body to clamp or release the blade, respectively, and cam means responsive to spring pressure and directly connected with the body and cap for shifting the latter laterally with respect to the axis of the screw means in substantially parallel relation to the body upon release of said screw means.

24. A safety razor comprising a body and a cap adapted to clamp an interposed blade having longitudinal cutting edges, a handle, co-operating screw means on the handle and cap for moving the latter toward or away from the body, means permanently and movably connecting the cap with the body and embodying a potential pivot mounting for the former ineffective as an axis of swinging of the cap while said screw means is engaged and becoming effective upon disengagement of the screw means to enable the cap to be swung upon an axis parallel with the longitudinal dimension of the cap and body, and means operable upon substantially the instant of disengagement of the screw means for maintaining said axis against transverse movement during swinging of the cap thereby maintaining the edge of the blade out of contact with the relatively moving component parts of the razor.

25. A safety razor comprising a body and a cap adapted to clamp an interposed blade having longitudinal cutting edges, a handle, co-operating screw means on the handle and cap for moving the latter toward or away from the body while maintaining parallelism therewith, means permanently and movably connecting the cap with the body and embodying a potential pivot mounting for the former including engaging elements on the body and cap, said screw means maintaining said pivot mounting ineffective as an axis of swinging of the cap until disengaged and then enabling the cap to be swung upon an axis parallel with the longitudinal edge of the body, and means for confining said elements to relative rotary movement except when the screw means is in substantial operative alinement so as to maintain the edge of the blade out of contact with the component parts of the razor.

26. In a safety razor comprising guard and cap members adapted to clamp a flexible blade into curved position therebetween, a flexible blade, and handle actuated screw means for moving the cap rectilinearly from and toward the guard member, means hingedly connecting the cap and guard members along a guard edge of the razor so the cap can have rotation about an

axis parallel to the edge of the blade, said means being such as will enable the cap to have substantial rectilinear movement from and toward the body during operation of said blade clamping means but during all stages of said rotation will confine the axis to unchanged relation with respect to all the component parts of the razor.

27. A razor comprising cap and body members adapted to have a blade interposed therebetween, the body having oppositely disposed guards on its longitudinal edges, means embodying pivotal elements permanently and movably associating a longitudinal edge of the cap with the adjacent edge of the body and enabling the members to have relative swinging movement, screw means embodying engageable and disengageable screw elements for moving the members into clamped or released relation to the interposed blade and establishing an axis of relative rotation for the members, the said axis being so established by a rectilinear shifting of said pivotal elements accompanying the relative moving of the members into released relation to the blade and when so established lying in position parallel to an adjacent longitudinal edge of one member and in temporary spaced parallel relation to the corresponding longitudinal edge of the other member, and means stabilizing the axis in said position during all stages of the relative swinging movement, whereby the edge of the blade is protected from damaging contact with the moving parts and whereby the elements of the screw means will be disposed in axial alinement upon return thereof to operative engagement.

28. A razor comprising cap and body members adapted to have a blade interposed therebetween with an edge of the blade protruding from between two corresponding edges of the members, the body having oppositely disposed longitudinal guards, means permanently and movably connecting the members by journal and bearing elements and enabling them to have relative swinging movement about an axis neighboring corresponding edges of said members, screw means for producing relative rectilinear movement of said members into clamped and released relation to the interposed blade, said axis being temporarily established by rectilinear movement of said elements in spaced relation to one of said members during releasing operation of said screw means, and means stabilizing the axis in said spaced relation during all swinging movements of the members.

29. A safety razor comprising a body member and a cap adapted to have a double edged flexible thin blade interposed therebetween for clamping engagement thereby when in shaving position, a handle, screw means carried by the handle and the cap for moving the latter into or out of clamping relation to the blade upon rotation of the handle in one direction or the other, means permanently movably connecting the cap with the body and enabling the cap to approach or recede from the body in substantial parallelism therewith upon operation of said screw means in one direction or the other, said connecting means maintaining the cap against rectilinear movement with respect to the body when the screw means is disengaged and providing a pivot enabling the cap to be swung laterally away from the body, the axis of rotation being maintained in fixed relation to the body and cap whereby the screw means will be restored to axial alinement upon subsequent swinging movement of the cap into superposed spaced relation to the body.

30. A safety razor comprising a body member and a cap adapted to have a flexible blade interposed therebetween for clamping engagement thereby when in shaving position, a handle, screw means carried by the handle and the cap for moving the latter into or out of clamping relation to the blade upon rotation of the handle in one direction or the other, means permanently movably connecting the cap with the body and enabling the cap to approach or recede from the body in substantial parallelism therewith upon rotation of the handle in one direction or the other, said connecting means maintaining the cap against movement other than pivotal with respect to the body immediately upon disengagement of the screw means and providing a pivot enabling the cap to be swung laterally away from the body in an arcuate path of constant radius, and means for maintaining the axis of rotation in fixed relation to the body and cap whereby the screw means will be restored to axial alignment upon subsequent swinging movement of the cap into superposed spaced relation to the body. 80

31. A safety razor comprising a body and a cap adapted to clamp an interposed blade, a handle, cooperating screw means on the handle and cap for moving the latter toward or away from the body, means permanently movably connecting the cap with the body and embodying a potential pivot mounting for the former ineffective as an axis of swinging of the cap while said screw means is engaged and becoming effective upon disengagement of the screw means to enable the cap to be swung upon an axis extending longitudinally of the cap and body, and spring means for maintaining said axis against transverse movement during swinging of the cap. 100
32. A safety razor comprising a body and a cap adapted to clamp an interposed blade having longitudinal cutting edges, a handle, cooperating screw means on the handle and cap for moving the latter toward or away from the body while maintaining substantial parallelism therewith, means permanently and movably connecting the cap with the body and embodying a potential pivot mounting for the former including engaging elements on the body and cap, said screw means maintaining said pivot mounting ineffective as an axis of swinging of the cap until disengaged and then enabling the cap to be swung upon an axis parallel with the longitudinal edge of the body, and spring means for confining said elements to relative rotary movement except when the screw means is in substantial operative alignment so as to maintain the edge of the blade out of contact with the component parts of the razor. 105
33. In a safety razor comprising guard and cap members adapted to clamp a flexible blade into curved position therebetween, a blade, and handle actuated screw means for moving the cap rectilinearly from and toward the guard member, means hingedly connecting the cap and guard members along a guard edge of the razor so the cap can have rotation about an axis parallel with the edge of the blade, said means enabling the cap to have substantial rectilinear movement from and toward the body, and spring means operable upon disengagement of the screw means for confining the axis of rotation of the cap to unchanged relation with respect to all the component parts of the razor. 85
34. A razor comprising cap and body members adapted to have a blade interposed therebetween, the body having oppositely disposed guards on its longitudinal edges, means embodying pivotal elements permanently and movably connecting a longitudinal edge of the cap with the adjacent edge of the body and enabling the members to have relative swinging movement, screw means embodying engageable and disengageable screw elements for moving the members into clamped or released relation to the interposed blade and establishing an axis of relative rotation of the members, the said axis being established by a rectilinear shifting of said pivotal elements accompanying the relative moving of the members into released relation to the blade and when so established lying in position parallel to an adjacent longitudinal edge of one member and in temporary spaced parallel relation to the corresponding longitudinal edge of the other member, and spring means stabilizing the axis in said spaced parallel relation during all stages of the relative swinging movement, whereby the edge of the blade is protected from damaging contact with the moving parts and whereby the elements of the screw means will be disposed in axial alignment upon return thereof to operative engagement. 90
35. A razor comprising cap and body members adapted to have a blade interposed therebetween with an edge of the blade protruding from between two corresponding edges of the members, the body having oppositely disposed longitudinal guards, means permanently and movably connecting the members by journal and bearing elements and enabling them to have relative swinging movement about an axis neighboring corresponding edges of said members, screw means for producing relative rectilinear movement of said members into clamped or released relation to the interposed blade, said axis being temporarily established by rectilinear movement of said elements in spaced relation to one of said members during releasing operation of said screw means, and spring means stabilizing said axis in said spaced relation during all swinging movements of the members. 105
